FRANZ C. REINHARDT, OF PATERSON, NEW JERSEY.

SHUTTLE.

Application filed October 22, 1927. Serial No. 227,877.

In the art of forming ribbon having double shots of filling, so as to give for instance the ribbed effect characterizing grosgrain, it has heretofore been deemed necessary to perform two successive shuttle passings, one for each shot, and to bind in the first shot by a crossing of a few of the warps before the other shot is effected and the main crossing of the warps performed, thus to prevent the possibility of the second shot of filling being caused partially or wholly to ride up on or cross the first shot so that they would not lie side by side in the plane of the fabric for its full width and hence produce a defect. This necessitated the loom performing two complete cycles or picks to produce a cross-rib—one for the first shot and its binding-in by a crossing of a few of the warps, and another for the second shot and the binding of both shots by the crossing of all of the warps. The object of this invention is to provide a shuttle in the use of which both shots of filling or weft thread can be effected at once and regularly incorporated in the fabric so as to lie side by side in its plane for its full width, thus greatly to increase production by making it possible to weave the same length of goods by one-half as many picks or cycles of the loom as heretofore.

In the drawing,

Fig. 1 is a top plan view of a shuttle embodying my invention;

Fig. 2 is a front elevation thereof;

35 Figs. 3 and 4 are sections on lines 3—3 and 4—4, Fig. 1; and

Fig. 5 is a plan of the fabric being formed and the shuttle laying the filling therein.

40 The shuttle 1 shown is of the bow type (here curved or arcuate in plan) and is equipped with the usual spring-pressed brake 2 to bear against and impose a certain degree of friction resistance on a supply 3 of filling, arranged to rotate on the spindle 4, all of which may be substantially as usual in bow shuttles excepting that the supply 3 is according to my invention composed of two filling threads *a* and *b* which are wound into a package forming such supply without twist around each other, as appears where they extend from the supply in Fig. 1.

45 The bow, 1^a, has two thread outlets 5—5 one on each side of its summit, where there is a thread-separating abutment 6. Through these outlets, which are in the ex-

ample narrow slits, are respectively extended the filling threads *a* and *b*. When the shuttle is in action, moving back and forth through the shed, first one thread and then the other will encounter the abutment and be held the closer to the fell, or as what I herein term the forward thread.

50 There is means arranged within the bow and in a line cutting its rises 1^b longitudinally of the shuttle to tension both threads. This is afforded by two guides 7 7, preferably elastically supported, as by springs 8 8 which may be affixed to the shuttle in holes 9 therein in a well-known way. The action 55 of this means, and more particularly of the two guides which in the present example constitute the same, will be hereinafter set forth. In the present example there is also auxiliary means to tension both threads, 70 to wit, a pair of guides 10 10, here elastically supported by springs 11 11 affixed to the shuttle in the same manner as springs 8 8 and preferably near the latter, and another pair of guides 12 12 arranged on a 75 staple 13 at the inside of the summit of the bow. When all these guides are used the preferable threading of the shuttle is that shown, where one thread extends through one series of guides 7, 10 and 12 and then through one outlet 5 and the other extends 80 through the other series of guides 7, 10 and 12 and then through the other outlet 5.

85 Each outlet 5 extends from the summit of the bow back substantially to the aforesaid line cutting the bow rises longitudinally of the shuttle, their rear termini being in Fig. 1 indicated by the dotted line 14.

90 In weaving with one shuttle I have found in practice that in order uniformly to produce grosgrain in which each two shots of filling shall lie side by side in the plane of the fabric for its full width it is necessary not simply that one thread should be held 95 forward of the other (as by abutment 6) but that they should be well spaced and that the rearward thread should be subject to inferior resistance: their ultimate side-by-side arrangement will be manifestly insured 100 if the forward thread has an appreciable lead on the other and also if it is so tensioned that it will exert superior pressure 105 in the convergence of the shed. This results in my construction mainly from placing the tension means 7 7 in a line cutting the rises 1^b of the bow longitudinally of the 110

shuttle and extending the outlets 5 back substantially to said line. For then, whereas one thread (see *b* in Figs. 1 and 5) is in either flight of the shuttle held forward 5 of the other and subject to resistance at 7 as well as at 6 the other thread is held well back of the first thread and is practically free of resistance at 7: note that 10 guide 7 for this latter thread is in Fig. 1 retracted by its spring against the rise of the bow, or inactive in tensioning, since the thread extends through it without deflection. In other words, when the shuttle is reciprocating in weaving devices 7—8 7—8 15 are alternately stressed by the threads, and the one which is not stressed then simply confines its thread to reeving in more or less a straight line and well back of the other or forward thread.

20 It is of course desirable that the forward thread be advanced by the pull of the shuttle as close as possible to the fell of the fabric 15 so as to reduce the likelihood of the reed 16 (see Fig. 5), in beating-up the two 25 threads, disturbing their relation as determined by the shuttle; hence, and also to insure complete take-up of the slack that would otherwise ensue in the first part of the shuttle's flight in either direction, it is best 30 to use auxiliary tension means, as 10 10 and 12 12.

35 This is the first instance, so far as I am aware, where, given a double-thread-delivering shuttle having a bow provided with a forward thread-separating abutment and thread outlets for the respective threads extending back from said abutment, such shuttle also has means independent of the abutment for imposing on that thread which is 40 held by the abutment relatively forward of the other thread on the flight of the shuttle in either direction tension exceeding the tension on the other thread.

45 An important element of my invention is the employment of a single supply 3 having the threads wound to form the package without twist around each other whereby, in the presence of means in the shuttle, as 6 and the guides which separates them, they can be 50 fed out of the shuttle without obstruction.

55 Where the bow presents in plan an arcuate outer face and has thread outlets one on each side of its summit and a thread-separating abutment at said summit and the outlets extend from the summit substantially to a line cutting the bow rises longitudinally of the shuttle, the thread which bends around the abutment can engage in the outlet for the other thread as shown at 60 17 in Fig. 1; in short, the salient which the curved outer face of the bow presents to the straight line which the thread naturally assumes is cross-sectionally bifurcated so as to receive the thread, which would otherwise roll off the bow, up or down, into a less fa-

vorably position for insuring the mentioned desired ultimate relation of the two threads. To insure the forward thread "finding" the outlet of the other thread in this way it is preferable to provide a groove 18 (Figs. 3 70 and 4) at the summit, which connects the two outlets.

Having thus fully described my invention, what I claim is:

1. A double-thread-delivering shuttle having a bow provided with a forward thread-separating abutment and thread outlets for the respective threads extending back from said abutment, said shuttle also having means independent of the abutment for imposing on that thread which is held by the abutment relatively forward of the other thread on the flight of the shuttle in either direction tension exceeding the tension on said other thread. 75

2. A double-thread-delivering shuttle having a bow provided with thread outlets for the respective threads one on each side of its summit and with a thread-separating abutment at said summit and also having means 80 to tension both threads arranged in a line cutting the bow rises longitudinally of the shuttle, said outlets each extending from said summit substantially to said line. 85

3. A double-thread-delivering shuttle having a bow provided with thread outlets for the respective threads one on each side of its summit and with a thread-separating abutment at said summit and also having elastic means to tension both threads arranged in a 100 line cutting the bow rises longitudinally of the shuttle, said outlets each extending from said summit substantially to said line. 95

4. A double-thread-delivering shuttle having a bow provided with thread outlets for the respective threads one on each side of its summit and with a thread-separating abutment at said summit and also having thread guides for the respective threads arranged 105 each in a line cutting the bow rises longitudinally of the shuttle, said outlets each extending from said summit substantially to said line. 110

5. A double-thread-delivering shuttle having a bow provided with thread outlets for the respective threads one on each side of its summit and with a thread-separating abutment at said summit and also having elastically supported thread guides for the 115 respective threads arranged each in a line cutting the bow rises longitudinally of the shuttle, said outlets each extending from said summit substantially to said line. 120

6. A double-thread-delivering shuttle having a bow presenting in plan an arcuate outer face and provided with thread outlets for the respective threads one on each side of its summit and with a thread-separating abutment at said summit, said outlets each extending from said summit sub- 125 130

stantially to a line cutting the bow rises longitudinally of the shuttle, whereby that thread which is held by the abutment relatively forward of the other thread on the 5 flight of the shuttle in either direction will engage in the outlet appertaining to the latter thread.

7. A double-thread-delivering shuttle having a bow presenting in plan an arcuate 10 outer face and provided with thread outlets for the respective threads one on each side of its summit and with a thread-separating abutment at said summit, said outlets each extending from said summit substantially 15 to a line cutting the bow rises longitudinally of the shuttle and the bow having at said summit an exterior thread-directing groove connecting the two outlets.

8. In combination, a shuttle having a 20 bow provided with two thread outlets one on each side of its summit and with a

thread-separating abutment at said summit, and a double-thread supply having the threads thereof wound into a package without twist around each other, said supply being revolubly supported in the shuttle and 25 said threads being adapted to extend respectively through the two outlets.

9. A double-thread-delivering shuttle having a bow and provided with thread outlets for the respective threads one on each side of its summit and with a thread-separating abutment, said outlets each extending back from said summit, and the shuttle having each side of said abutment means to 30 receive and hold against displacement up or down relatively to the bow that thread, which trailing the shuttle when in flight, extends around said abutment.

In testimony whereof I affix my signature. 35

FRANZ C. REINHARDT.
